UNITED STATES PATENT OFFICE

**RAYMOND E. PATTEN, OF OAK PARK, ILLINOIS, ASSIGNOR TO EDISON GENERAL ELECTRIC
APPLIANCE COMPANY, INC., A CORPORATION OF NEW YORK**

DESIGN FOR A WAFFLE IRON

Application filed July 20, 1931. Serial No. 40,603. Term of patent 14 years.

To all whom it may concern:

Be it known that I, RAYMOND E. PATTEN, a citizen of the United States, residing at Oak Park, in the county of Cook, State of Illinois, have invented a new, original, and ornamental Design for a Waffle Iron, of which the following is a specification, reference being had to the accompanying drawing, forming a part thereof.

The accompanying drawing shows a perspective view of a waffle iron embodying my new design.

I claim:

The ornamental design for a waffle iron substantially as shown.

In witness whereof I have hereunto set my hand.

RAYMOND E. PATTEN.
